QUICK-DISCONNECT CONNECTOR

Neil D. Bingham, Inglewood, and Rene J. Beauregard, Los Angeles, Calif., assignors to Radio Corporation of America, a corporation of Delaware

Application January 27, 1956, Serial No. 561,835

3 Claims. (Cl. 339—75)

This invention relates to electrical connectors, and more particularly to a connector which provides a quick means for electrically and mechanically connecting and disconnecting separate units of electrical equipment.

As electronic equipment has become more and more complicated, it has been necessary to divide various portions of such equipment into a number of separate units which are connected together by external leads. This allows complete units to be replaced or removed without interfering with the connections of the remaining equipment. For example, the equipment may have three or four sub-assemblies constructed as separate units which might plug in to the other units to comprise the complete equipment.

An object of this invention is to provide an improved connector for electrically and mechanically joining a pair of electrical units.

Another object of this invention is to provide a novel electrical connector wherein the electrical contact elements are protected against accidental damage when the connector parts are separated.

A further object of this invention is to provide a novel electrical connector which incorporates a rigid mechanical coupling and wherein the connector elements are capable of being readily coupled and uncoupled.

In accordance with the present invention, a connector comprises two portions, each of which may be fixed to an individual unit or chassis, and each including a housing. One housing encloses conductive plug elements and the other housing encloses conductive socket elements. One housing is dimensioned to be received telescopically within the other. The outer housing includes a clamp, a portion of which is integral with this housing. The clamp is readily clamped over the inner housing by means of a single bolt or screw when the connector portions are assembled. The clamp holds the plug and socket elements in engagement with each other and provides a rigid mechanical coupling between the connector portions.

The novel features of the invention, as well as additional objects and advantages thereof, will be understood more fully from the following description when read in connection with the accompanying drawing, in which:

Figure 1 is a view in plan of a connector assembly in accordance with the present invention;

Figure 2 is a view in side elevation, partly in section, taken along the line 2—2 of Figure 1 looking in the direction of the appended arrows;

Figure 3 is a sectional view taken along the line 3—3 of Figure 2 looking in the direction of the appended arrows; and

Figure 4 is a view in plan of a pair of connectors in accordance with the present invention used for connecting two units of electrical equipment.

Referring now in more detail to Figures 1, 2 and 3 of the accompanying drawing, an illustrative embodiment of a connector in accordance with the present invention is illustrated and described. The connector is comprised of two portions. A first connector portion 11 comprises

a housing 13 in the form of a cylindrical sleeve and a structure 15 by means of which the housing is attached to electrical equipment or to a cable. Enclosed within the housing 13 and substantially flush with the open face of the housing is a socket member 17 having conductive socket elements 19. These socket elements 19 extend inwardly from the face of the socket member and are disposed in any desired arrangement.

A second connector portion 21 comprises a housing 23 in the form of a cylindrical sleeve and a structure 25 for attaching the housing to electrical equipment or to a member of such or similar equipment. The housing 23 includes a flange 24 which may be used for mounting the housing in some applications. The housing 23 encloses a plug member 27 having conductive plug elements or pins 29 extending outwardly from its face. Means are provided within each of the connector portions for connecting conductors to the plug and socket elements.

The inner diameter of the sleeve housing 23 is slightly larger than the outer diameter of the sleeve housing 13 so that the housing 13 is received snugly, yet readily, within the housing 23 when the connector portions are assembled. The plug member 27 is set back from the open end of the housing 23 to permit the housing 13 to be received within the sleeve housing 23. This provides the advantage that the pins 29 do not extend beyond the open face of the housing 23 and therefore are protected against unintentional damage when the connector portions are in a separated condition.

In order to provide a means for rigidly connecting the two connector portions, a form of clamp 31 is provided which is an extension of the housing 23. A portion of this clamp 31 is formed by an axial extension 33 of the housing 23. This extension 33 includes substantially one half of the circumference of the housing 23. The clamp 31 is in the form of a ring clamp and the extension 33 forms substantially one half of the ring clamp. The two edges of the extension 33 which lie parallel to the axis of the housing 23 will be referred to as the ends of the extension.

The remaining half of the clamp 31 is formed from an arcuate member 35 having dimensions which are substantially the same as those of the extension 33. One end of the arcuate member 35 is joined in hinged or pivoted relationship with one end of the extension 33. The hinged connection is illustrated, in Figure 3, to be in the form of a scarf joint wherein each of the members forming the clamp is provided with a tab or hook 37. These tabs or hooks are interlocked to form a pivotal joint.

The ends of the members 33 and 35 forming the clamp, which are remote from the hinged ends, are each provided with a flange 39. These flanges 39 are provided with bores which are aligned perpendicular to the axis of the housing 23 and are substantially tangential to the housing 23. The bore in one of the members is smaller and is tapped to receive the threaded portion of a screw 41. The ends of the clamp members 33 and 35, having the flanges 39, are separated slightly so that the clamp may be drawn together by the screw 41 to a circumference which is less than the inner circumference of the housing 23. The housings 13 and 23 are dimensioned to slide together easily, and yet the clamp 31 is readily tightened to positively lock the housings together.

The above described clamp will be held together when the housing 23 is separated from the housing 13 by means of the screw 41 and through the resiliency of the arcuate member 35 which will prevent the hinged joint from becoming separated.

An additional means for supporting the clamp is provided. This means includes an annular groove 28,

provided in the plug member 27, in cooperation with inwardly extending annular ribs 34 and 36 provided on the clamp portions 33 and 35, respectively. This means permits the clamp to be readily opened and closed and maintains the movable clamp portion 35 in alignment with the housing 23.

With the above described arrangement the clamp 31 is substantially an integral part of the housing 23. The connector portions are engaged and disengaged readily by relative movement in an axial direction. The rigid mechanical coupling between the connector portions is very readily made or broken merely by turning the screw 41 with a screw driver, for example. The connector itself may be difficult to reach, yet the connection may be easily made and broken if the head of screw 41 can be reached by a suitable tool.

In order to provide for the proper orientation of one of the connector portions with respect to the other, so that the pins 29 will be inserted in the proper sockets 19, the housing 23 is provided with a tab 43 (Figure 3) which extends inwardly from its inner surface. The housing 13 is provided with a groove 45 at its outer surface which extends from its face in a direction parallel to the axis of the housing. This groove 45 is dimensioned to receive the tab 43 and permits the connector portions to be assembled together only in one relative rotational position.

Referring now to Figure 4 of the accompanying drawing, a pair of connectors is shown providing the means for electrically and mechanically connecting two equipment units 10 and 20. In this embodiment only one pin and socket element are illustrated for each connector. When used in this manner, it is not necessary to provide means, such as the tab 43 and the groove 45, for properly orientating connector portions relative to each other, since the relative positions of the units will likely be obvious. In an assembly such as is illustrated in Figure 4, the electrical and mechanical connection between the two electrical units may be easily and readily made even though the connector assembly itself may be difficult to reach. The units are assembled by moving the movable unit toward the fixed unit in a direction axially of the connector portions. The only requirement for making the mechanical connection then is that the heads of the bolts 41 can be reached by a suitable tool. By means of this arrangement the inserted unit is rigidly connected to the remainder of the electrical equipment.

What is claimed is:

1. An electrical connector comprising a pair of sleeves dimensioned for telescopic engagement, a member fixed in one of said sleeves having at least one conductive plug extending therefrom in a direction parallel to the axis of said one sleeve, a member fixed in the other of said sleeves having a conductive socket in register with said plug, the larger of said sleeves having a longitudinal

extension comprising substantially one half of the circumference of said sleeve, an arcuate member, means for interlocking one end of said arcuate member with one edge of said extension to form a hinged clamp, means associated with the ends of said extension and said arcuate member opposite from said interlocking means for adjustably maintaining said ends in substantial abutting relationship, the smaller of said sleeves having an annular groove in its external surface adjacent to the end thereof, and said hinged clamp having means on its internal surfaces defining an annular rib adapted to be received in said annular groove.

2. A connector coupling comprising a first portion having a circular cross section at one end, a conductive socket mounted in said first portion, a second portion including a circular sleeve at one end, a conductive plug mounted within said sleeve, means defining a ring clamp associated with said sleeve, said means including an axial extension of substantially one half the circumferential wall of said sleeve, an arcuate member, means pivotally connecting said arcuate member to said extension along a line parallel to the longitudinal axis of said sleeve, means for adjustably connecting said extension and said arcuate member at a point diametrically opposite from said pivot means to form a substantially complete extension of said sleeve, said first portion of said coupling having an annular groove adjacent to said one end thereof, and said ring clamp extension of said sleeve having means on the internal surfaces thereof defining an annular rib adapted to seat in said annular groove.

3. A connector coupling comprising a first portion having a circular cross section at one end, a plurality of conductive socket elements mounted in said first portion at said circular end, a second portion including a circular sleeve at one end, a plurality of conductive plug elements mounted in said sleeve, means defining a ring clamp extension of said sleeve, said means including an axial extension of one half the circumference of said sleeve and an arcuate member, said axial extension and said arcuate member being pivotally connected along a line parallel to the longitudinal axis of said sleeve, means adjustably connecting said extension and said arcuate member at a point opposite from said pivotal connection, said second portion having an inwardly extending tab, and said first portion having a longitudinal groove on its outer wall for cooperation with said tab to orient said first and second portions rotationally with respect to each other.
